US00D926296S

(12) **United States Design Patent** (10) Patent No.: **US D926,296 S**
(45) Date of Patent: **** Jul. 27, 2021**

(54) **WATER HOSE NOZZLES**

(71) Applicant: **Neoperl GmbH**, Müllheim (DE)

(72) Inventors: **Werner Kury**, Müllheim (DE); **Daniel Oechsle**, Müllheim (DE); **Holger Reinhardt**, March-Buchheim (DE); **Jürgen Höppner**, Müllheim (DE)

(73) Assignee: **Neoperl GmbH**, Müllheim (DE)

(**) Term: **15 Years**

(21) Appl. No.: **35/508,614**

(22) Filed: **Jan. 20, 2020**

(80) **Hague Agreement Data**

Int. Filing Date: **Jan. 20, 2020**

Int. Reg. No.: **DM/205873**

Int. Reg. Date: **Jan. 20, 2020**

Int. Reg. Pub. Date: **Feb. 14, 2020**

(51) **LOC (13) Cl. 23-01**

(52) **U.S. Cl.**

USPC **D23/262**

(58) **Field of Classification Search**

USPC D23/213, 226, 232-237, 259, 260,
D23/262-267; D8/382, 396

CPC F16L 27/12; F16L 37/1225; F16L 5/02

(57) **CLAIM**

The ornamental design for water hose nozzles, as shown and described.

DESCRIPTION

4.-6. Water hose nozzles

4.1 : Top

4.2 : Perspective

4.3 : Bottom

4.4 : Perspective

4.5 : Left

4.6 : Front

4.7 : Right

4.8 : Back

5.1 : Top

5.2 : Perspective

5.3 : Bottom

5.4 : Perspective

5.5 : Left

5.6 : Front

5.7 : Right

5.8 : Back

6.1 : Top

6.2 : Perspective

6.3 : Bottom

6.4 : Perspective

6.5 : Left

6.6 : Front

6.7 : Right

6.8 : Back

The broken lines represent portions of the water hose nozzles in which the design is embodied that form no part of the claimed design.

1 Claim, 24 Drawing Sheets
